UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 34,735, dated July 2, 1901.

Application filed June 6, 1901. Serial No. 63,471. Term of patent 7 years.

To all whom it may concern:

Be it known that I, WILLIAM T. SMITH, a citizen of the United States, residing in Philadelphia, Pennsylvania, have invented and produced a certain new and original Design for a Woven Fabric, of which the following is a specification.

My design is shown in the accompanying drawing, which represents sufficient of the pattern to illustrate the design, the remainder of the pattern being merely a repetition of what is shown.

The design comprises a ground 1, having parallel bars or stripes of different colors or shades of color, and figures 2 and 3 overlying the same. The figure 2 has a central ornament 4, with a step-like outline, and this is surrounded by a series of zigzag or step-like bands 5, 6, 7, and 9 of different colors or

shades of color. The figure 3 is located at 20 the corner of the design and consists of three zigzag or step-like bands 10, 11, and 12, enclosing a triangular space containing geometrical figures.

Having thus described my invention, I 25 claim and desire to secure by Letters Patent—

The design for a woven fabric, substantially as described and as shown in the accompanying drawing. 30

In testimony whereof I have signed my name to this specification in the presence of two subscribing witnesses.

WILLIAM T. SMITH.
